UNITED STATES PATENT OFFICE

WALTER B. ENGH, OF CHICAGO, ILLINOIS, ASSIGNOR TO THE MANTLE LAMP COMPANY
OF AMERICA, OF CHICAGO, ILLINOIS, A CORPORATION OF ILLINOIS

LAMP WICK

Application filed June 15, 1928. Serial No. 285,509.

The invention relates to the preparation of wicks for use in the oil burners, the principal object of the invention being to produce a wick which, while substantially filling the space between the wick tubes of an annular burner, will have desired external and internal dimensions, whereby undue frictional engagement with said wick tubes is avoided, excessive evaporation of the oil is avoided, and the operation of the burner is improved.

The method of weaving a cotton wick together with the normal and unavoidable variations in the yarn from which wicks are made, precludes the production of a wick which, when taken from the loom, will be of such size and thickness as to operate with maximum efficiency in an annular burner, and this is especially true if said burner is of the blue-flame type wherein minute variations in the relative dimensions of parts and in small adjustments of the wick which vary its vapor generating surfaces, result in substantial changes in the proportioning of vapor and air upon which the character of the mantle-heating flame is dependent.

It is, therefore, desirable to produce a wick wherein the exterior and the interior diameter are such that the wick will properly fit and fill the space between the outer and inner wick tubes of an annular burner, and this result is attained by the method hereinafter fully described.

The wick is sized for the inner and the outer diameter only at the upper portion thereof where it moves within the top of the burner, the lower parts of the wick being left the same as when they come from the loom.

In carrying out the steps necessary to the production of the new wick, a metal sleeve of the proper length and having an interior diameter of the correct size is employed for sizing the outside of the wick, and within this sleeve a tubular gummed paper or cloth tape is positioned with the gummed side in. After a wick is received from the loom, it is wet only on the outside at the upper end, and, after folding, it is inserted inside the gummed tape. Then it is straightened out against the tape, the finger of the operator being conveniently employed for this purpose.

The next operation consists in using an inner metal tube for the inside of the wick, a tape having a gummed surface on the outside, being employed. This tube, on which said tape is exteriorally mounted, is forced into the wick which should be dry on the inside so that the gummed surface of the tape will not stick to and will slip within the wick without difficulty.

The whole construction is then placed within an oven and heated so that the water on the outer surface of the wick steams and penetrates the fibers thereof sufficiently to cause the gummed surface of the inner tape to adhere to the inner surface of the wick, the wetted outer surface of the wick meantime adhering to the gummed tape surrounding it. This operation is continued in an oven until the wick is thoroughly dry. Then the wick is removed and the two metal tubes are separated from the wick.

If a wick having sufficient stock material has been used, it will be found that the interior diameter and the external diameter of the wick, as thus made, will be exactly the same as the corresponding dimensions of the metal tubes which supported the gummed tapes while the wick was in the oven. It is possible to make a wick by this method to fit the space within the wick tubes of a burner very accurately and within close limits, and also to produce a wick devoid of any longitudinal folds or creases which often act as paths for the escape of vapor from the wick at times when the burner is over-heated and vapor is formed within the wick tube.

Experiments have shown that a lamp is far more reliable when the wick fits the inner tube and the outer tube properly, and has a minimum of clearance between the wick and the wick tubes. An excessive clearance between the wick and the outer wick tube has a tendency to make the burner sensitive, and, at the same time, unreliable when the burner is highly heated, there being, under that abnormal condition, possible vaporization within the clearance space.

The sizing of the wick on the outside and the inside by tape, also stiffens the wick and forms inner and outer surfaces which slide

within the wick tube very freely. After the wick has been treated as already described, the upper extremity is trimmed and charred.

The invention will be best understood if reference is made to the accompanying drawing in which the figure shows the completed wick in vertical section, the metal sleeves which size the wick being still in operative positions.

10 Referring to the drawing—

1 is the wick, the outer reinforcing gummed tape being indicated by the numeral 2, and the inner reinforcing tape being indicated by the numeral 3.

15 4 and 5 are the outer and the inner metal sleeve which, as explained, are employed in sizing the external and the internal diameter of the wick.

The gummed tapes 2 and 3 are to be applied 20 to the upper portion of the wick only, the lower portion of said wick being left in a loose condition so that it will readily absorb the oil in which it is submerged when in use.

The upper portion of the wick is to a certain extent compacted by the sizing operation, 25 the result being a diminution of the size and an increase in the number of the capillary ducts thereof, as well as an increase in the oil-raising capacity of the wick whereby an adequate supply of oil to the flame is insured. The wick, as woven, is made somewhat oversize, so as to allow for the compression produced by the sizing operation.

Also, since the upper portions of all the 35 sized wicks are necessarily compacted to the same extent, said wicks possess uniform capillary functions, uniformity in the oil-raising capacities of different wicks being highly advantageous because blue-flame burners 40 equipped with wicks having varied capilarities do not receive equal quantities of fuel, and, consequently, fail to produce like mixtures of vapor and air.

The adhesive elements of the tapes may be 45 such as are soluble in water or other solvents, or of the kind that become sticky when heated.

Having thus described the invention, what I claim is:

50 1. A woven annular cellulose wick for a burner of the blue-flame type, having a lower portion, and a compacted upper portion encircled by a restrictive tape extending to the top thereof for maintaining the desired circumference of said wick.

55 2. A woven annular cellulose wick for a burner of the blue-flame type, having a normal and loose lower portion, and a compacted upper portion enclosed by an adherent tape 60 and interiorally lined with an adherent tape.

65 3. The process of treating an annular woven cellulose wick, which consists in lining the upper portion of said wick with an adherent tape, applying an adherent tape to the outside of said upper portion, and compacting

said upper portion to thereby give it a desired circumference.

4. The process of treating an annular woven cellulose wick, which consists in applying to the upper portion of said wick exterior and interior adherent tapes, compacting said upper portion to give it a desired size, and subjecting said upper portion to heat.

5. The process of treating an annular wick, which consists in wetting the exterior upper surface of said wick, applying to the upper portion of said wick exterior and interior tapes coated with a soluble adhesive, and sizing and compacting said upper portion while allowing the moisture of said wetted exterior surface to penetrate the fibers of the wick and dissolve the soluble adhesive of the inner tape.

6. The process of producing a wick, which consists in weaving a tubular fabric of slightly larger diameter than the completed wick, and then compacting one end of said tubular fabric to thereby reduce it to the desired size.

In testimony whereof I affix my signature.

WALTER B. ENGH.
